RABBIT HUTCH

William C. Havens, Pampa, Tex.

Application February 15, 1951, Serial No. 211,095

2 Claims. (Cl. 119—17)

1

This invention relates to animal pens and the like and more specifically comprises novel and useful improvements in a rabbit hutch.

It is a primary object of this invention to provide a multi-deck rabbit hutch.

It is a further object of this invention to provide a multi-deck rabbit hutch in which units may easily be added or subtracted in superposed levels.

Another object of this invention is to provide a multi-deck rabbit hutch embodying the foregoing objects which includes a means for discharging the animal's excrement.

Other objects of this invention are to construct a rabbit hutch which has provisions for portability and mobility, which is ventilated, which has interior visibility, which has feeding troughs, locked doors and partitioned compartments.

These, together with various ancillary objects and features of the invention which will later become apparent as the following description proceeds, are attained by the device, a preferred embodiment of which has been illustrated by way of example only in the accompanying drawings, wherein:

Figure 1 is a front vertical view illustrating two decks or units of the instant invention;

Figure 2 is a vertical end view taken from the right-hand side of Figure 1;

Figure 3 is a vertical sectional view taken along the section line 3—3 of Figure 1;

Figure 4 is a vertical longitudinal sectional view taken on the plane of section line 4—4 of Figure 2;

Figure 5 is a horizontal longitudinal sectional view taken on a plane of section line 5—5 of Figure 1;

Figure 6 is an enlarged fragmentary sectional view taken along the plane of section line 6—6 of Figure 1.

With reference now being made to the accompanying drawings wherein like numerals designate similar parts throughout the various views, it will be noted that the numeral 10 denotes a rabbit hutch of multiple or multi-deck housing units. For purposes of explanation, only two such units, namely, an upper and a lower unit, 12 and 14, respectively, have been shown but it is to be understood that any number of such units, similarly constructed, could be employed.

At the outset it should be understood that the lower unit 14 of each system or stack of units is the only one constructed in a special manner. All of the superposed units are to be identically constructed.

2

Actually, the lower unit 14 is unique only in the manner of its support and this is due to its position in the stack of units. Accordingly, in Figures 2 and 3, it will be noted that this lower unit consists of a framework seen generally at 16, around its entire contour. The vertical portions of this framework comprise front and rear legs 18 and 20, respectively, constructed in such a manner as to provide a horizontal support for the frame 22 to which is secured a foraminous floor 23. A dropping board 24a is disposed beneath the floor 23 and is secured to the legs of the framework 16. As will be noted, particularly from Figures 2 and 3, the board 24a is inclined downwardly from the front to the rear of the framework to guide droppings through the floor 23 to the rear of the framework so that such droppings will not collect underneath the framework.

The framework 16 is such that the legs extend for the entire vertical height of the unit at their particular locations and it will be seen that the front legs 18 are relatively longer than the rear legs 20. In this mode, the roof 24 may be supported at an inclined level as seen best in Figure 2. Further, by referring to Figure 5, there is illustrated the roof 24 of a solid, preferably metallic material covering the entire lower unit 14. To complete the general outer construction of this lower unit, there are provided side walls 26 of wire mesh having any suitable dimensions and attached along all of the edges to the adjacent framework 16.

Considering the interior of the lower unit 14, it will be evident from Figures 1, 3 and 4 that the housing space is divided into two compartments by a feeding trough 28 and a manger 30. Both the trough and manger extend from the front to the rear of the unit achieving their support through suitable portions of the framework 16. The bottom of the trough rests flush with the floor 23, and is substantially an elongated rectangular solid box-like feed container, being conventional in nature.

The manger 30, on the other hand, is substantially an elongated V-shaped section having its apex secured along the medial longitudinal line of the trough 28, as at 32. The sides of the manger rise angularly upwardly to the roof 24 of the unit. The top 34 of the manger is made of sheet metal or some solid material while the lower half has a wire mesh 36. This lower portion, therefore, provides sufficient openings through which the animals may nibble on the 55 fodder or the like.

Each compartment is provided at the front thereof with a door 38, 40, each of which is hinged for horizontal swinging movement. To lock the doors, a latch 42 is utilized as in Figures 1 and 6 and consists of a resilient plate 44 pivotally secured to the framework 16, as at 45, and having a projecting key 46 for removable insertion in the complementary slots, as 48, in the adjacent portions of the doors.

The superposed housing units are identical in all respects to the bottom unit 14 except for the construction of the legs. Accordingly, the upper unit 12 is provided with the general outer framework 16 having a foraminous floor 50, walls 52 of wire mesh, a trough 54 and manger 56 dividing the unit into two compartments and hinged doors, as 58, being locked by the latch 60.

Attention now being directed to the legs of the upper unit 12, it will be noted that the front leg 62 extends only throughout the vertical height of the housing unit itself, thereby allowing the lower framework 64 of the upper unit to rest on the upper horizontal ledge of the roof 24 of the lower unit 14. However, the rear leg 66 depends below the upper unit 12 to such an extent that when the leg 66 rests upon the lower portion of the roof 24, the floor 50 will be in a substantially horizontal plane. In this manner, therefore, the inclined roof 24 cooperates with the relative length of the legs 66 and 62 to provide a horizontal foraminous floor 50 with a discharge chute for the animal's excrement situated below.

It will be understood that these legs 62 and 66 are provided with pins 68 depending therefrom and which slidably fit within apertures or blind holes 70 in the adjacent upper surfaces of the roof 24. Therefore, upper units 12 may be added as desired each providing a cooperative relationship between the lower legs and the next adjacent lower roof.

Finally, to add a greater mobility to the multi-deck arrangement of rabbit hutches, there is provided rollers 72 at the lower ends of the lower legs 18 and 20 as seen in the accompanying drawings.

From the foregoing, the construction and operation of the rabbit hutch will be readily understood and further explanation is believed to be unnecessary. However, since numerous modifications and changes will be readily apparent to those skilled in the art after a consideration of the foregoing specification and accompanying drawings, it is not desired to limit the invention to the exact construction shown and described, but all suitable modifications and equivalents may

be resorted to, falling within the scope of the appended claims.

Having described the invention, what is claimed as new is:

- 5 1. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 10 2. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 15 3. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 20 4. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 25 5. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 30 6. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 35 7. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
- 40 8. A multi-deck rabbit hutch comprising upper and lower housing units, each of said units having side walls, a horizontal foraminous floor and an inclined solid roof, the lower unit having apertures at the corners of the roof, the upper unit having a peripheral frame supporting the floor thereof, the forward portion of said frame abutting the upper edge of said lower roof, pins depending from the forward corners of said frame and being slidably received in corresponding roof apertures of the lower unit and means associated with the rear corners of said frame for angularly supporting said frame with respect to the lower roof, said means comprising spaced legs depending from the rear corners of the peripheral frame, pins mounted on the free ends of said legs, said pins being slidably received in corresponding roof apertures of the lower unit.
